W. FLETCHER

PUMP GOVERNOR

Filed Feb. 11, 1924

FIG. 2.

INVENTOR=
Wilford Fletcher,
By Clyde L. Rogers
his ATTORNEY

UNITED STATES PATENT OFFICE.

WILFORD FLETCHER, OF BILLERICA, MASSACHUSETTS.

PUMP GOVERNOR.

Application filed February 11, 1924. Serial No. 691,869.

This invention relates to pump governors of the type wherein the valve which controls the supply of steam or other motive fluid to the motor element of the pump is governed 5 automatically by the water pressure from the discharge connection of the pump, and whereby the motive fluid is cut off or reduced when pressure on the discharge side of the pump reaches a predetermined maximum. In pump governors of this kind it has been customary to provide connections from the discharge pipe of the pump leadings to a cylinder containing a piston connected with the stem of the motive fluid supply valve, the pressure of water in this arrangement acting directly upon the valve controlling piston and against a spring or like resilient backing to exert pressure tending to close the valve. This arrangement 10 has been subject to the objection that the packing of the valve controlling piston has been constantly subject to the deteriorating action of the water acting thereon, this water being virtually trapped in the piston cylinder and hence by reason of its practically stationary condition tending more rapidly to corrode and disintegrate the piston and its packing. This deteriorating action 15 of the water is still more in evidence when the apparatus is used only at intervals with the result that the piston is apt to stick in its cylinder and not respond freely to the pressure conditions of the water; further when the system is pumping hot water and 20 with the small leakage which usually soon develops around the piston packing, the water in contact with the piston becomes hot and hence tends to injure the piston packing still more rapidly.

25 The principal object of the present invention is to obviate these objections by providing means whereby oil is substituted for water as the fluid contacting with, and acting directly upon the valve-controlling piston. In accordance with my invention I attain this object by providing means whereby a suitable quantity of oil or other lubricating fluid is held trapped and contained in such a way as to be directly subject to the 30 pressure conditions of the pump discharge water. A further object is to provide a simply constructed device which does not add appreciably to the dimensions of, or in any way interfere with, the usual set-up of 35 the valve-controlling mechanism, and which is conveniently arranged for the supply and

replenishment of the oil, and also easily kept clean. The foregoing and other objects and advantages of the invention will more fully appear from the following detailed description taken in connection with the accompanying drawings, and the distinctive features of novelty will be pointed out in the appended claims.

Referring to the drawings:

Fig. 1 is a vertical sectional view showing a pump governor device equipped with the invention; and

Fig. 2 is a side elevation showing the arrangement and application of the invention to the ordinary steam pumping equipment.

10 indicates a steam pump which may be of usual type, it being here understood that the reference to steam as the motive fluid is merely illustrative and intended to typify any suitable motive fluid. The motor end 10^a of this steam pump is equipped with the usual steam pipe connection 11 having interposed therein the valve housing 12, which contains the controlling valve 13. 15 The pump end 10^b has a usual discharge pipe 14 leading therefrom, with a small pipe 15 connected to the discharge pipe and leading to the upper portion of the housing structure which contains the controlling piston connected with the valve 13. This controlling piston indicated at 16 is equipped with a usual or suitable packing and is fitted in a cylinder 17 borne at the top of an open housing 18 which contains an adjusting device 19 interposed in the stem 20, which extends upward from the valve 13 and bears the piston 16 at its upper extremity. A compression coil spring 21 is fitted 20 in the lower part of the cylinder 17 to react upward against the piston 16 and normally keep the valve 13 open. In accordance with my invention a cylinder 22 is secured to the top of the cylinder 17, this cylinder 22 having a bottom web 22^a with a shroud 22^b 25 depending therefrom which is internally threaded to engage the top of the cylinder 17. The cylinder 22 has also its upper end closed as indicated at 22^c with a plug 22^d tapped therein to permit convenient replenishment of the cylinder with oil. This cylinder thus constitutes a closed chamber, and the pipe connection 15 leads into the lower portion thereof, as shown with an interposed usual globe valve 23, so that the water pressure may be shut off when desired. The bottom web 22^a has the lower ends of

two small pipes 24, 25 tapped thereinto, these pipes extending upwardly through the cylinder 22 with one thereof, shown as the pipe 25, extending upward somewhat 5 farther than the other, i. e. very close to the top 22° of the cylinder, while the other pipe 24 terminates at a slightly lower point. The upper ends of these pipes are open and they thus afford communication from the top of 10 the cylinder 22 to the top of the piston cylinder 17. 26 indicates a small plug tapped into the lower portion of the cylinder 22 to facilitate the cleaning out thereof when required. In use the plug 22° being removed 15 the cylinder 22 is filled with oil which then flows down the shorter pipe 24 to fill the space in the cylinder 17 above the piston 16, this being permitted by the air vent then afforded by the pipe 25. Then as pressure 20 water from the discharge pipe 14 is forced into the bottom of the cylinder 22 it will, by reason of its higher specific gravity remain in the lower portion of said cylinder, and the body of oil trapped in the cylinder 25 22 will remain always on top of the water surface, so that so long as any oil remains in the cylinder 22, it will be forced downward through the pipe 24 into the space above the piston and hence the piston will 30 operate at all times in the presence of oil and be kept entirely free from the deteriorating action of the pressure water. With this arrangement the supply of oil in the cylinder 22 will last for long periods, it being understood that the piston 16 in practice only has a range of movement of about one inch, and when the oil is nearly exhausted, it may be simply and easily replenished as described. I am aware that 35 the invention may be embodied in other specific forms without departing from the spirit 40

or essential attributes thereof, and I therefore desire the present embodiment to be considered in all respects as illustrative and not restrictive, reference being had to the appended claims rather than to the foregoing description to indicate the scope of the invention.

Having described my invention, what I claim as new and desire to secure by Letters Patent is:

1. The combination with a steam pump equipped with a valve controlling the supply of motive fluid thereto, said valve having an upwardly extending stem with a 55 controlling piston at the upper end thereof, a cylinder in which said piston is fitted equipped with a backing spring, and an oil containing chamber borne at the top of said cylinder having a connection with the 60 pump discharge, and having also a conduit leading from the top portion thereof downward through the bottom thereof, and opening into the top of the piston cylinder.

2. The combination with a steam pump 65 equipped with a valve controlling the supply of motive fluid thereto, said valve having an upwardly extending stem with a controlling piston at the upper end thereof, a cylinder in which said piston is fitted 70 equipped with a backing spring, and an oil containing chamber borne at the top of said cylinder having a connection with the pump discharge, and having also two conduits leading from the top portion thereof downward and opening into the top of the piston cylinder, one of said conduits extending nearer the top of said chamber than the other for the purpose stated.

In testimony whereof, I have signed my 80 name to this specification.

WILFORD FLETCHER.
